UNITED STATES PATENT OFFICE.

ADDISON J. SOUDERS, OF EAST AKRON, OHIO.

WINDOW-SHADE ROLLER.

Application filed October 23, 1922. Serial No. 596,325.

To all whom it may concern:

Be it known that I, ADDISON J. SOUDERS, a citizen of the United States, residing at East Akron, in the county of Summit and 5 State of Ohio, have invented a new and useful Window-Shade Roller, of which the following is a specification.

This invention relates to shade curtain rollers and has for its object the provision 10 of a shade roller having an improved spring anchoring cap which may be formed from sheet metal.

Another object is the provision of novel 15 means for mounting the pawls and assembling the several parts.

Further objects will present themselves 20 as the description proceeds, it being within the province of the disclosure to improve generally, devices of that class to which the present invention belongs.

It is also to be understood, that slight 25 changes may be made in the device, within the scope of what is claimed, without departing from the spirit of the invention or sacrificing any of the advantages thereof.

In the drawing:

Figure 1 is a view of the device in elevation, there being parts shown in section.

Figure 2 is an end elevation of the device.

Figure 3 is a section on line 3—3 of Figure 1.

Figure 4 is a longitudinal section taken on line 4—4 of Figure 3.

Figure 5 is a longitudinal section taken 35 on the plane as indicated by line 5—5 of Figure 2.

Figure 6 is a sectional view taken on line 6—6 of Figure 1, and

Figure 7 is a fragmental sectional view 40 on line 7—7 of Figure 3.

Referring to the drawings by characters of reference, the numeral 1 indicates a shade curtain roll, and since the present invention relates only to the anchored end of the 45 curtain roll, but a small portion of the roll is shown in the drawing, it being understood that the opposite end of the roll is equipped with the usual bearing pin to provide for rotation.

The roll 1 has the usual bore 2 in which is located the spring 3, and a rod 4, on which the spring is wound, is provided with a slot 5, in which one end of the spring is anchored. The structure just described be-

ing that usually employed in shade curtain 55 rolls.

The rod 4 has inserted in its outer end the stem 6 of a bearing bar which is secured to the rod by means of an anchoring pin 7, a ferrule 8 surrounds the end of the rod 60 4 and is reduced in diameter as shown at 30, defining a shoulder 31. The bearing bar is provided with notches 9 for a purpose to presently appear and the outer end thereof is reduced at 10 to form attaching means 65 for connection with the supporting bracket (not shown). Arms 32 are formed on the stem 6 and engage slots 33 formed in the portion 30 of the sleeve 8, the arms preventing rotation of the sleeve on the rod 4. 70

A cap 11 is provided with a central opening 12 in which the reduced portion 30 of the sleeve rotates. The cap 11 is provided with an inturned circumferential flange 13, the flange being of approximately the same 75 diameter as the roll 1. Tongues 14 are stamped from opposite edges of the member 11 and turned inwardly pass through the openings 15 in a disk 16, the ends being bent to engage the disk and secure the same to 80 the cap, the edge of the disk is supported on the flange 13, forming a compartment 18 between the cap 11 and the disk 16. Pawls 19 are located in the compartment 18, the 85 pawls having openings 20 through which the tongues 14 extend, thereby providing pivotal connection for the pawls. Fingers 21 formed on the pawls are adapted to engage notches 32 cut in the reduced portion 30 of the sleeve. 90

Hooks 22 are formed from portions of the disk 16 the said hooks being shaped to conform to the curvature of the disk and adapted to receive and hold a coil of the 95 spring at that end remote from the slot 5, the end of the spring being formed into a hook 23 to prevent retraction from the hook 22. Lugs 24 are struck out at right angles from the surface of the member 16 and are seated in the end of the roll to secure the 100 device to the end of the curtain roll.

The pawl casing defined by the cap 11 and plate 16 rotate on the reduced extension 30, said extension providing a bearing for the same, the slots 32 serving as abutments for 105 the pawls and the notches 9 permit the fingers 21 to seat in the slots.

It is to be observed that the device can

be formed from sheet metal of few parts and is not liable to become damaged in use.

Having thus described the invention, what is claimed is:—

- 5 1. In a device of the class described; a pair of members comprising a cap having a central opening and a plate spaced from the cap; a flange formed on the cap to effect the said spacing of the cap and plate;
- 10 10. tongues formed from one of said members for connecting the two members and pawls located in the space between the cap and plate, the pawls being pivotally mounted on the tongues.
- 15 15. 2. The combination with a curtain roll having a central bore, a rod located in the bore and a spring carried by the rod, one end of the spring being anchored to the rod, of a cap having a central opening, a plate

spaced from the cap, tongues formed on the 20 cap for connecting the cap and plate, pawls mounted on the tongues between the cap and plate and oppositely disposed members formed from the metal of the plate for anchoring the other end of the spring, each 25 of said members comprising a tongue reversely bent longitudinally of the axis of the roll to form a hook, and bent circumferentially of the roll to conform to the shape of the springs.

In testimony that I claim the foregoing as my own, I have hereunto affixed my signature in the presence of two witnesses.

ADDISON J. SOUDERS.
